UNITED STATES PATENT OFFICE

ARTHUR J. BOYNTON, OF CHICAGO, ILLINOIS, ASSIGNOR TO H. A. BRASSERT & COMPANY, OF CHICAGO, ILLINOIS, A CORPORATION OF ILLINOIS

APPARATUS FOR CHARGING BLAST FURNACES

Application filed September 1, 1928. Serial No. 303,421.

This invention relates to a new and improved method of operating blast furnaces, and more particularly to a method of distributing the charge within such furnaces and to apparatus for carrying out such methods.

As is well known in the art, the blast furnace of the vertical shaft type is charged from above usually by means of a charging bell construction. The charge consists of coke, ore and a fluxing material such as limestone. With the use of the normal charging bell, the charged material slides from the surface of the bell toward and against the inner periphery of the furnace chamber at the stock line. The material is deflected and some rolls down toward the center, but the normal condition of burden in the upper portion of the furnace is in the shape of an inverted cone, being lower at the center and higher at the periphery. It will be apparent that in this method of charging the larger pieces of the material will tend to roll down toward the center while the finer particles remain adjacent the periphery.

The necessity for this annular charging proceeds from causes now well understood. It has been determined by experiment that, in the normal operation of the blast furnace, combustion takes place only within a relatively short radius from each of the tuyères. This combustion affects an approximately spherical area adjacent each of the tuyères and does not extend to the central portion of the charge in the plane of the tuyères. The charge in the furnace moves downwardly mainly because of the reduction in volume caused by the combustion at these points and there is also a minor movement in response to withdrawal of slag and of iron from the furnace. It has been found that this lowering or downward movement of the charge takes place in a manner similar to the movement within a circular bin from which the material is withdrawn at spaced periph-

eral points. There is only slight movement of the material in the center of the furnace and there is a cone shaped core extending well up into the furnace which is maintained without substantial movement during the 50 operation. Due to the nature of the charging, this central core is largely composed of the larger pieces of coke.

The products of combustion from the combustion area adjacent the tuyères rise through the mass of material in the furnace and it is their function in the lower portion of the furnace to melt the ore and slag material, and in the upper portion of the furnace to reduce the ore. In order to carry out these 60 functions it is necessary that the gases be brought in intimate contact with the material. To accomplish this result the material should be of substantially uniform permeability so as to avoid channeling by 65 the gases.

In the combustion zone, the combustion gases do not more than slightly penetrate the central core or cone which is formed mainly of closely packed coke. The gases 70 rise directly through the mass in the annulus above the small combustion zones adjacent the tuyères. The gases rise substantially vertically until they encounter partially melted iron and slag in the course of melting. 75 At this point the viscosity of the mass and its resistance to the flow of gases becomes greater. Such melting, however, in view of the methods of charging now in use and the limited combustion areas, takes place in an 80 annular zone adjacent the furnace walls. At this point in the upward path of the gases where the resistance in the outer zone becomes greater, the central portion, composed mainly of coke, offers less resistance to the flow of the 85 gases.

There is accordingly a tendency to force the gases passing upwardly toward the center of the furnace at this level. This results in a loss of the proper heating and reducing effect 90

by the gases in outer annulus containing the greater portion of the ore. Above this point the distribution of the gases will depend on the relative total resistance of the stock column at the center of the furnace and at the sides. The effect of the usual annular charging is to increase the density of the charge in the annulus around the sides. In addition to the presence of the ore in this annulus, the average size of the coke is somewhat less than that found at the center of the furnace.

According to the present invention, I have provided a method and means whereby the permeability of the central core may be controlled so that the proper proportion of gases may be directed through the outer annular mass of material.

It is an object of the present invention to provide a new and improved method and apparatus for the operation and charging of blast furnaces or the like.

It is a further object to provide a method whereby the coke may be sized and controlled as to the point of deposit in the furnace.

It is an additional object to provide apparatus whereby the various elements of the charge may be selectively directed towards the center or the periphery of the furnace chamber as desired.

It is also an object to provide a method and apparatus of this character which are simple in design and operation and which may be applied to and carried out with existing structures without material alterations therein.

Other and further objects will appear as the description proceeds.

In the accompanying drawings I have shown somewhat diagrammatically one form of apparatus for carrying out my improved method.

In the drawings—

Figure 1 is a fragmentary section of the upper portion of a blast furnace or the like with the charging bell in closed position;

Figure 2 is a view similar to Figure 1, but showing the charging bell lowered and the deflecting members in operative position.

In the drawings the upper portion of the furnace has been designated 10 and the usual charging hopper 11 is shown extending into the upper portion of the furnace. A usual type of charging bell 12 extends up into the hopper 11 and closes the lower portion of the hopper.

It will be understood that this showing is diagrammatic and that any usual form of bell controlling and operating means may be utilized. Such features form no part of the present invention and have been omitted from the drawings for the sake of clearness.

The secondary deflecting ring 13 is shown suspended from the bell 12 by means of the links 14. It will be noted that while the circumference of the upper edge of the ring

13 is greater than that of the lower edge of the bell 12, the ring is so placed as to be out of the path of material normally flowing from the bell 12. To charge material toward the periphery of the furnace chamber the bell 12 carrying the ring 13 is lowered to the dotted line position of Figure 1.

The secondary deflecting member or ring 15 is shown in Figure 1 as drawn up around the hopper 11. Any desired means may be provided for raising and lowering this deflecting member 15. As shown in Figure 2, the ring 15 is so proportioned as to fit upon the upper edge of the ring 13, so that the two rings will together form a continuous deflecting surface. The ring 15 is thus interposed into the path of material flowing from the bell 12 and deflects this material inwardly and downwardly upon the ring 13.

In the operation of the furnace, according to my improved method, with the use of this apparatus, the coke will be separated as to size and the larger coke will be charged together with the ore and fluxing material. For the purpose of charging this material, the ring 15 will remain in the position shown in Figure 1. The deflecting ring 13 will have no effect upon the charge which will be distributed in the usual manner. The finer coke will be charged separately with the parts in position shown in Figure 2. By this means the finer coke will be directed toward the center of the furnace so that the slowly moving column of material in the center of the furnace will have as its major constituent this fine coke. The central column may thus be rendered no more pervious than the surrounding annulus and the gases will be forced to pass upwardly through the outer annulus of fuel, ore and flux. It will be understood that the permeability of the central mass may be controlled by properly proportioning the sizes and quantities of the elements of the charge and controlling their distribution into the furnace. The other elements of the charge may be sized and proportioned if desired, and the central and annular charging so controlled and related as to give any desired condition of the furnace charged.

While I have shown one preferred form of apparatus for carrying out my invention, and described certain methods of operation, the methods may be carried out in other ways, and with the use of other forms of apparatus, and I contemplate such changes and modifications as come within the spirit and scope of the appended claims.

I claim:

1. In a blast furnace, a charging bell, an inwardly inclined deflecting device located within the furnace below the bell and out of the path of material discharged from the bell, and means adapted to receive material from the bell and discharge it upon the deflecting device.

2. In a blast furnace, a charging bell, an inwardly inclined deflecting member suspended from and below the bell, and a second inwardly inclined deflecting member supported in the furnace and adapted to be selectively brought into position in upward prolongation of the deflecting member suspended from the bell.

Signed at Chicago, Illinois, this 29th day of
August, 1928.

ARTHUR J. BOYNTON.
